UNITED STATES PATENT OFFICE.

OLIVER O. APP, OF NEW YORK, N. Y.

POWER-ACTUATED IMPLEMENT.

1,263,835.

Specification of Letters Patent. Patented Apr. 23, 1918.

Application filed April 3, 1911. Serial No. 618,543.

To all whom it may concern:

Be it known that I, OLIVER O. APP, a citizen of the United States, residing at the city of New York, in the borough of Manhattan and State of New York, have invented certain new and useful Improvements in Power-Actuated Implements, of which the following is a full, clear, and exact description.

This invention relates to power driven implements, and more particularly to power mechanism for operating chisels, drills, and the like, such as are used in tunneling and excavating work and for breaking stones and other frangible material. My invention has for its object the provision of reciprocable means adapted to forcefully impinge against the tool holding part, or directly against a portion of the tool itself, said means being preferably mechanically driven in one direction and pneumatically driven in the reverse or contrary direction. A further object of my invention is to conserve the pressure-fluid used in the operation of the device, so that waste of the same is substantially obviated. A still further object of my invention is to provide a driving mechanism for said reciprocable means which is adapted to be driven continuously in one direction. I have further devised novel means for angularly or rotarily advancing a tool while the latter is in operation; this feature being of especial value, in drilling holes in rock, and the like. An other object of my invention is to provide novel means whereby a tool carried by the implement is automatically set in operation when the working portion or edge thereof is forcibly driven against a surface to be operated upon; while it is correspondingly automatically thrown out of action when pressure upon the said tool is relieved. I have further devised means whereby the reciprocating part or hammer is thrown into such a position as to be inoperative when the pressure upon the tool is removed in manner aforesaid. These and other objects of my invention will be hereinafter referred to and more particularly pointed out in the appended claims.

In the drawings which form a part hereof, and in which like characters designate like parts throughout the several views:

Figure 1 is a side elevation of one embodiment of my invention.

Fig. 2 is a plan of the same.

Fig. 3 is a vertical longitudinal section of the cylinder shown in Fig. 1, taken axially thereof; the parts contained in said cylinder being in operative relationship.

Fig. 4 is a view similar to Fig. 3, but showing the parts in inoperative position.

Fig. 5 is a detail section drawn to a reduced scale, said section being taken on the line V—V of Fig. 3.

Fig. 6 is a detail, partly in section, of the cam and wiping parts hereinafter referred to; the section being taken on line VI—VI of Fig. 7.

Fig. 7 is a detail elevation of the elements shown in Fig. 6; some of said elements being broken away on line VII—VII of said figure.

Fig. 8 is a detail of the tool and water connection.

Fig. 9 is a detail of a non-revolvle tool and parts coöperating therewith.

In the implement shown in the figures, which, as I am well aware, is but one form of many in which my invention, or essential features thereof, may be embodied, a base 1 is provided upon which is mounted a cylinder 2 in any suitable manner, as by means of uprights or standards 3, 4 and 5, the cylinder being held in place upon said standards by means of straps 6. This cylinder may be of substantially the same bore throughout, and has positioned interiorly thereof a separator block or partition 7, which is secured firmly in position in said cylinder. The joint between said block and cylinder is preferably packed as at 8 to prevent leakage of fluid therethrough. Block 7 is apertured as at 9 to neatly receive a piston rod 10 which carries a piston 11, said piston being seated against a shoulder 12 of the rod and being held in place by nuts 13—14; the reduced portion 15 of the rod extending out through a cap 16 which is preferably threaded onto the rear extremity of the cylinder. The forward end of the piston rod 10 is preferably headed as at 17, and in this exemplification of my invention this head is hexagonal in cross-section and is received into a correspondingly shaped recess 18 formed in a sleeve 19, which sleeve has substantially the same outer diameter as the bore of the cylinder, but is revoluble and also longitudinally displaceable therein. The head 17 is adapted to impinge against the shank 20 of the tool or of a tool-holder 20' of suitable descrip-

tion, according to the use to which the implement is intended to be put, the said shank in either case, being preferably firmly keyed or pinned to the sleeve 19, as at 21. A 5 second sleeve 22, which may be of the same diameter as the first, is arranged in the cylinder between the outer sleeve 19 and the partition block 7 above referred to, and uniting devices such as the bars or clips 10 23 are preferably provided, whereby the outer sleeve 19 and inner sleeve 22 are held together, clips 23 being preferably substantially U-shaped in cross-section and being arcuately formed to conform to 15 the bore of the cylinder; the ribs 24 of these bars or clips being received into corresponding grooves in respective sleeves. By reason of this construction these two sleeves are constrained to move longitudinally together, but the sleeve 19 is free to 20 rotate independently of the inner sleeve 22, and to facilitate such action ball-bearings 25 may be provided between the said sleeves, these ball-bearings being of any suitable 25 construction. The clips 23 may if desired each be semicircular, as indicated in Fig. 4, the extremities of said bars abutting against each other as at 26 in said figure. The inner sleeve 22 is reduced in diameter or 30 grooved as at 27 and 28 so that in effect this sleeve constitutes a double valve the use of which will be hereinafter set forth. Packing rings 29, 30 and 31, are carried by said sleeve and are so disposed as to prevent 35 leakage from groove 27 to groove 28 or vice versa, or from either of said grooves toward or from either end of the said sleeve.

The rear extremity of the cylinder is ported as at 32, and the body thereof is 40 correspondingly ported at 33, the said ports being in communication by means of a passage or conduit 34 which in this instance is formed directly in the wall of the cylinder, although obviously other constructions may 45 be employed. Two additional ports 34' and 35 are preferably arranged between ports 32 and 33, ports 34' and 35 being connected together by means of a conduit 36. In the opposite side of the cylinder shown in Fig. 50 3, an additional pair of ports 37 and 38 are indicated which are in communication with each other through a conduit 39; this conduit in turn opening at 40 into a pipe 41 which communicates with a compressed air 55 tank 42. By reason of the disposition of port 37 with respect to the rear end of the inner sleeve, it is evident that this sleeve and thereby also the outer sleeve 19, will be normally urged outwardly to the position 60 in which they are shown in Fig. 4, if pressure sufficient to overcome this tendency be not applied to the tool carried by said sleeve. The sleeves and the tool may hence be said to have a bias toward this position.

65 Assuming that such pressure has been ap-

plied, and that the sleeves are disposed as shown in Fig. 3; herein the port 38 is in communication with the groove 37 and the said groove is further in communication with port 33 and, via conduit 34, with port 70 32. Hence, the pressure fluid will pass through the several ports and passages, and will exert its pressure upon the rear wall of the piston 11, thereby urging said piston forwardly and driving its head 17 into contact with the tool-holder shank 20. As the pressure in the tank is maintained substantially constant, unless the piston is forcibly withdrawn from this last mentioned position, it will tend to stay there indefinitely 75 so long as pressure is applied upon the working edge or portion of the tool.

Assuming now that the pressure upon the tool is relieved and that thereby the fluid pressure upon the rear end of the sleeve 22 80 forces both sleeves into their outermost position, it will be seen that port 38 will first be closed by the passage of the ring 30 and adjacent parts of the sleeve thereover, but will immediately afterward be again opened 85 and thrown into communication with groove 28, as shown in Fig. 4. The fluid will then find its way through said groove to port 35, and will pass thence through conduit 36 and port 34' into the chamber 90 formed between the rear wall of the partition block 7 and the front wall of the piston, which will force the piston rearwardly into the position shown in Fig. 4. The ports 43, which in this instance extend through 95 walls of the cylinder, are so disposed that when the sleeve 22 is in its outermost position groove 27 will be in communication with the outer air therethrough, which permits the pressure fluid, in this instance compressed air, which had previously been introduced behind piston 11, to escape so that said piston may be driven rearwardly to the end of its travel.

Referring to Figs. 2, 3 and 4, it will be 10 observed that additional exhaust ports 44-44 are provided which when the sleeve 22 is in its innermost position are in communication with groove 28. Accordingly 11 the chamber in front of piston 11 is at such time always in communication with the atmosphere, while when the sleeve 22 is moved forwardly into the position shown in Fig. 4, ports 44 are closed by the rear extremity 12 of said sleeve.

Referring again to Figs. 1 and 2, and particularly to the details shown in Figs. 6 and 7, it will be observed that the rear end of the base 1 carries bearing brackets 45 in which is journaled a shaft 46, which 13 is driven by a motor or prime mover 47, which latter is also carried by the base 1. Substantially midway between the brackets 45 and in alignment with the cylinder 2 is a cam wheel or element 48, which in this in- 14

stance is provided with three cams 49 of substantially the configuration shown in Fig. 1. The cam surfaces are adapted to engage rollers 50 which are mounted upon 5 studs 51 disposed in the respective extremities of the arms 52 of a bifurcated or U-shaped frame 53. This frame is secured to the rear extremity of the reduced portion 15 of the piston rod and in such 10 manner that the said piston rod is journaled therein, and is free to rotate when driven in the manner hereinafter described. The cam plate 48 carries one or more wipers 54 which are preferably adjustably mounted 15 thereon as shown in Figs. 6 and 7 wherein the cam plate is dovetail-recessed or grooved at 55 for the reception of the shank 56 of a wiper 54, the shank being clamped in its position in the groove by means of a bolt 20 or screw 57, said shank being slotted as at 58 to permit radial movement inwardly or outwardly of said wiper with respect to the cam plate. The finger-like portion 59 of the wiper is adapted for engagement with 25 a friction bevel wheel 60, the latter being carried upon the threaded extremity of the piston rod, and being secured firmly there-to so that said rod may be rotated by means of said bevel wheel. It may be noted in 30 this connection that the bifurcated frame 53 is revolvably mounted upon a sleeve 61, the extremities of which latter are in engagement with washers 62 and 63, washers 62 bearing against the hub of wheel 60, and 35 the respective washers and the said wheel being adapted to be clamped firmly to this sleeve by means of nuts 64 and 65.

Considering next the details shown in Fig. 8, the tool-holder shank, 20, has integrally formed therewith a chuck or tool-holder 66 which is annularly grooved as at 40 67 for the reception of a ring 68, which latter is held in place by means of a washer 69, which latter may be secured to the chuck 45 in any suitable manner, as by means of screws 70. The ring 68 is apertured and threaded as at 71 for the reception of a water pipe 72 and an annular conduit or 50 space 73 is provided between the chuck and the inner side of the ring 68, which is in communication with this pipe, while a cross conduit 74 extends through the chuck from 55 one side of this space to the other, and affords means for delivering flushing or lubricating fluid, such as water, from the pipe 72 to a centrally disposed vent 75.

The chuck is laterally apertured as at 76 for the reception of gripping blocks 77, which may be of wood, or other suitable 60 material, said blocks being held in contact with the shank of a tool 78, which is inserted axially into said chuck, by means of pressure blocks 79 which are disposed in contact with the gripping blocks 77, being 65 held thereagainst by means of a U-bolt 80,

the legs of which extend through apertures in the chuck located upon either side of the apertures 76, and the body or transverse portion of this U-bolt is adapted to bear directly against a wedge-block 81. This latter 70 is provided with a threaded extension 82 upon which is mounted a nut 83 while nuts 84 are provided upon the respective legs of the U-bolt 80.

In positioning a drilling tool 78, or the like, in the chuck, the shank of said tool is inserted into the chuck, and the gripping blocks are caused to firmly grip said shank therebetween; pressure being applied to said blocks first by means of nuts 84, and when these have been tightened up as far as practicable, the wedge 81 is drawn downwardly by means of nut 82 so that the tool shank is held very securely by the chuck. The shank of this type of tool is preferably apertured 85 longitudinally thereof as at 85, and in order to substantially prevent leakage of the water, which is intended to be passed through this aperture, I provide a packing ring or sleeve 86 which is received into a recess 87, 90 in the rear end of the tool-shank and into a corresponding recess 88, which is disposed around the opening or port 75. This packing ring may be of rubber, or any other suitable material, and it is obvious that, when 95 the tool is in position in its chuck, the water, or other flushing or lubricating fluid, may be delivered to the working edge or portion 89 of the tool from the pipe 72, and this in spite of the fact that pipe 72 is stationary, while 100 the chuck and tool are rotating more or less rapidly.

The shaft 46 is extended beyond the uppermost bracket 45, as viewed in Fig. 2, and operates a pump 90 by means of an eccentric strap 91, the construction employed for effecting the operation of the pump being that of any well known type. This pump is in communication with the compressed air tank via a pipe 92. It will hence be seen 105 that the tool and the necessary equipment for operating the same are so united as to constitute substantially a unit.

The operation of the apparatus is as follows: The electric motor 47 is driven at, let us say, 1,000 revolutions per minute, and of course, correspondingly the cam wheel 48 will be rotated at the same speed. The pump 90 will be actuated by the rotation of the shaft 46, and will deliver compressed air, if 115 that be the pressure fluid used, to the tank 42. Assuming that the tool has not been applied to the work, the sleeves 19 and 22 will then be in their outermost positions, and the pressure fluid, will exert its pressure upon 120 the forward face of the piston, driving such piston to the rear. In this position the rollers 50 which are indirectly carried by the piston rod, will be driven toward the shaft 46 and will thereby clear the cams 49 when 130

the latter are being rotated. The piston will therefore remain stationary; while correspondingly the sleeves 19 and 22 will be held in their outermost position by the action 5 of the pressure fluid upon the rear end of sleeve 22.

Assuming now that the tool is brought to bear against a rock surface, sleeve 19 and thereby sleeve 22, will be driven inwardly. 10 Communication between the respective ports will be established as per Fig. 3, which will result in fluid pressure being exerted upon the rear face of piston 11, while the forward face of said piston will be subject merely to 15 atmospheric pressure. The piston will accordingly be driven forward. The head 17 of the piston rod will impinge against the tool shank and the tool will be driven forcibly against the rock. This action, of course, 20 takes place assuming that the fluid pressure is admitted with sufficient rapidity to force the piston rod through its entire travel forwardly, before the rollers 50 encounter one of the sets of cam surfaces 49. In practice, 25 usually, in this initial actuation of the tool, the pressure block of the piston will, owing to the relative slowness with which the ports are opened when the sleeves are being driven inwardly, be insufficient at first to so move 30 the piston rod its entire stroke before the rollers 50 encounter the rapidly moving cams 49 and the respective rollers will hence each be struck by a cam at some point along the surface of the latter, before the head 17 35 has actually encountered the tool shank. This, however, merely concerns the initial operation of the device. The cam surfaces 49 having engaged the rollers 50, will retract the piston against the action of the pressure 40 fluid, but as soon as the respective points 93 of the cams which are in engagement with the rollers, pass said rollers, the piston will be free to be driven abruptly and powerfully forward by the pressure fluid, the piston 45 being thereafter periodically pulled back against the action of the pressure fluid and suddenly released. In this exemplification of my invention there are three sets of cams upon a cam wheel, and as the said wheel is 50 rotating at the rate of, let us say, 1,000 revolutions per minute, it is obvious that the piston head 17 will impinge against the tool shank approximately 3,000 times per minute, and that the force which the said head 55 will exert under said conditions will be relatively enormous if the pressure fluid be highly compressed.

In pneumatic tools as ordinarily constructed, the fluid operates expansively, and 60 hence the full pressure of the fluid is not available at the instant that the hammer strikes the tool or tool-carrying part. In my construction, however, practically no expansion whatsoever need occur and substantially the full pressure of the fluid is

available to urge the head or hammer forward, and to drive the same into contact with the tool or tool-carrying part up to the very instant of impact.

The tool further is held firmly to the work 70 so that it does not tend to rebound by reason of the pressure exerted upon the sleeve 22. Should it be desired to revolve or rotate the tool while operating the same, the wipers 54 are moved outwardly with respect to the 75 shaft 46 until they are adapted to successively engage the surface of the bevel wheel, each at an instant when the said wheel is in its most rearward position. As a result the wheel will be wiped, preferably somewhat 80 lightly, by the wipers, and will accordingly be rotated a small amount each time that a wiper engages it. As the bevel wheel is firmly secured to the piston rod and as the 85 head of the rod, in this instance, is non-circular, *i. e.*, hexagonal, the sleeve 19 will rotate with the rod and wheel, and will thereby impart a step by step angular or rotary movement to the tool; and by adjusting the 90 wipers with respect to the wheel the amount of rotary displacement of the tool, at each step, can be regulated.

Of course it is to be understood that it is not always desirable to employ a rotarily acting tool, as for instance when it is desired to merely use a chisel. In such case means are provided for preventing the tool and the sleeve 19 in which it is preferably directly held in such case, from rotating; auxiliary holding or locking means being 95 provided. Figs. 2 and 9 exemplify one form of such means, the cylinder having therein a transverse aperture 94 adapted for the reception of a key 95, which may be driven thereinto. The outer surface of the 100 sleeve 19 at one point is correspondingly surfaced off as at 96, said surface bearing against the inner side of the key 95 and thereby preventing the sleeve from rotating, while the depression or recess so formed in 105 the surface of the sleeve is of sufficiently greater width than that of the said key to permit of the necessary longitudinal displacement of the sleeve with respect to the cylinder. A normally non-revolvble tool, 110 has been shown in Fig. 9, and in this case no chuck being necessary, the shank of the tool is made hexagonal, in correspondence with the shank of the holder previously described, and is inserted directly into the hexagonal bore of the sleeve 19; the key 21 serving in this instance to maintain the tool 115 directly in position in said sleeve, instead of being in engagement with the shank of a tool holder.

In its broad aspects, the invention contemplates the provision, in combination with other parts, of a chamber of variable capacity which is adapted to be maintained 120 distended by the action of the pressure-fluid, 130

a part of which chamber is periodically movable by means of a suitable appliance so as to reduce the volume of said chamber, against the action of the pressure-fluid; the

5 abrupt action of the fluid in re-distending the chamber being utilized to drive the tool.

In the form of my device shown in the accompanying drawings this chamber is constituted by the rear end of the cylinder, its 10 cap and the piston; but it is evident that many types of chamber may be provided and that this distending action of the pressure-fluid may be taken advantage of in many ways; a number of which I am well 15 aware of.

I am also aware that some attempts have been made heretofore to utilize some of the underlying principles hereof and hence do not attempt to claim such a pressure chamber and means, broadly, for reducing its 20 volume against the action of the pressure fluid; that the employment of a cam as a part of the actuating means renders the device most practical and economical in operation. Especially is this the case when the 25 cam is revolvably mounted and when auxiliary means such, for example, as those shown are provided for automatically throwing the tool out of action when it is removed from 30 its work.

Having thus described my invention, I claim:

1. In a power-actuated implement, a fluid-pressure reservoir, a tool, a cylinder, a piston 35 therein, a movable valve for alternately admitting fluid-pressure to and exhausting fluid-pressure from each end of said cylinder, and means for retracting said piston against the action of the fluid-pressure admitted to one end of said cylinder.

2. In a power-actuated implement, a fluid-pressure reservoir, a tool, a cylinder, a reciprocably mounted element therein adapted to actuate said tool, a movable valvular means 45 for alternately admitting and exhausting fluid-pressure from each end of said cylinder, said means normally admitting pressure to the front end of said cylinder and exhausting it from the rear end and means 50 operatively associated with said tool for moving said valvular means to admit pressure to the rear end and to exhaust pressure from the front end of said cylinder, and means for retracting said element against 55 the force of said fluid pressure admitted to the rear end of said cylinder.

3. In a power-actuated implement, a fluid-pressure reservoir, a tool, a cylinder, a piston therein, a valve for controlling the admission of fluid-pressure to each end of said cylinder, said valve normally admitting pressure to the forward end, a tool, and means operatively associated with said tool 60 for moving said valve to cut off the supply of pressure to the forward end and to admit

it to the rear end of the cylinder and separate means for retracting said piston against the action of the fluid-pressure on the rear end of the piston.

4. In a power-actuated implement, a cylinder, a piston therein, a tool adapted to be actuated thereby, means for alternately admitting fluid-pressure to and exhausting fluid-pressure from each end of said cylinder, and means for retracting said piston against 70 the force of said fluid-pressure in one direction.

5. In a power-actuated implement, a fluid-pressure reservoir, a tool, a cylinder, a piston therein adapted to actuate said tool, 80 movable means for alternately admitting fluid-pressure to and exhausting fluid-pressure from each end of said piston, the movement of said movable means being controlled by the fluid-pressure in one direction, and 85 means operatively associated with said tool for controlling it again in the other direction.

6. In a power-actuated implement, a tool, a cylinder, a piston therein, means connected therewith for operating said tool, normally closed means for admitting fluid-pressure to one end of said cylinder for driving said piston forwardly and means operated by the backward movement of the tool for 95 opening said last-named means, and separate means for retracting said piston against the action of said fluid-pressure.

7. In a power actuated tool, a cylinder, a piston therein, a longitudinally displaceable 100 sleeve therein, movable inwardly toward said piston and away therefrom, said sleeve normally occupying the latter position, means for admitting pressure-fluid to one side of said piston when said sleeve is moved inwardly, means for retracting said piston against the action of said pressure-fluid, a tool carried by said sleeve, means for cutting off the admission of said pressure-fluid to said side of said piston when said sleeve 105 and tool move outwardly with respect to said piston.

8. In combination, a ported cylinder, a piston therein, a plurality of sleeves in said cylinder one of which is rotatably mounted, 115 one of said sleeves having pressure fluid passages therein, the movement of said last mentioned sleeve with respect to said cylinder controlling the admission of pressure fluid into said cylinder, a tool operable by said piston, 120 said tool being operatively connected to one of said sleeves, said sleeves adapted for co-action with each other and with said cylinder, whereby pressure upon the working portion of the tool controls the admission of pressure fluid to parts of said cylinder, means for positively displacing said piston against the action of said pressure fluid, and means for rotating said rotatably mounted sleeve.

9. A power-actuated implement comprising 130

ing a reciprocably mounted element, a tool adapted to be actuated thereby, pneumatic means for actuating said reciprocating element in one direction, mechanical means for actuating said element in the other direction, said pneumatic means being normally inoperative and said mechanical means being disassociated from said element under normal conditions and means controlled by the backward movement of the tool for rendering said pneumatic means operative and

for connecting said mechanical means to said reciprocably mounted element to thereby cause the periodical reciprocation of said element.

15

In witness whereof, I subscribe my signature, in the presence of two witnesses.
